WILLARD S. STUART, OF EAST HARTFORD, CONNECTICUT, ASSIGNOR TO THE BILLINGS & SPENCER COMPANY, OF HARTFORD, CONNECTICUT, A CORPORATION OF CONNECTICUT

NUT AND PIPE WRENCH

Application filed February 15, 1930. Serial No. 428,633.

The present invention relates broadly to the art of tools and involves more particularly a novel nut wrench which is characterized by certain new and desirable features over the now known tools of this character.

More specifically, the invention relates to a tool wherein the tightening action of the gripping jaws takes place incident to turning of the tool in one direction. In the subject wrench this effect is obtained with a toggle-like action, one arm of the toggle being constituted by the work itself and the other arm by the shorter arm of the tool. Conversely, a reversal of direction of rotation 15 of the tool results in a quick release of the work.

The aim of the present invention is to provide a tool of this sort which may be readily adjustable so as to accommodate work of 20 various sizes within relatively large ranges, the adjustable arrangement being such that undue wear on the pivot member or bolt is avoided; and there are relatively large bearing surfaces between the arms adjacent their 25 pivoted ends so that the arms do not become cocked or tilted one relative to the other. With the present arrangement, the jaws have a relatively wide effective range of movement at each position of adjustment so that various 30 sizes of work are accommodated and there is no gap in the sizes of work which can be gripped by the tool.

Other objects will be in part obvious and in part pointed out more in detail herein- 35 after.

The invention accordingly consists in the features of construction, combination of elements and arrangement of parts which will be exemplified in the construction hereinafter set forth and the scope of the application of 40 which will be indicated in the appended claim.

For a full and more complete understanding of the invention, reference may be had to 45 the following description and accompanying drawings, wherein:

Figure 1 is a side view in elevation of a 50 nut wrench made in accordance with the present invention. This view develops the wrench in one adjusted position.

Figure 2 is a plan view of the wrench shown in Figure 1.

Figure 3 is a section through the adjustable connection taken about on the plane indicated by the line 3—3 of Figure 1.

Figure 4 is a cross section through one of the arms. This view is taken on the line 4—4 of Figure 1.

Figure 5 is a cross section through the other arm taken on the line 5—5 of Figure 1, and

Figure 6 is a diagrammatic showing of the wrench when adjusted to accommodate the largest size work.

Referring now to the drawings, the wrench is shown comprising a comparatively long arm 10 and a shorter arm 11. At one end the arm 10 is flattened out as shown at 12, and this flattened portion is formed with a jaw face 13 having a suitable roughened surface such as one provided by ribs 14. At its other extremity the arm 10 is also flattened out, bent over, and somewhat enlarged, as illustrated at 15. This portion 15 is formed with an opening 16 of non-circular cross section for a purpose to be later more fully de- 75

scribed. The shorter arm 11 is deformed at one end to provide a curved jaw face 17 which is complementary to the jaw 13. This jaw 17 also has ribs 14 provided thereon for obvious reasons. At the other end the arm 11 is enlarged at one side and flattened out as shown at 18. A slot 19 is formed in this portion. At intervals the slot 19 is enlarged to provide openings 20, there being three of these openings in the illustrated embodiment, although this number is, of course, susceptible of variation. It is noteworthy that the slot 19 is inclined with respect to the arm 11.

A bolt 21, having flattened sides as shown at 22, and a head 23, is passed through the opening 16 with the head 23 bearing against the surface of the flattened portion 15. This bolt is held against rotation with respect to the arm 10 by the non-circular formation of the opening 16 and the bolt itself. This bolt 21 passes through the slot 19 which is dimensioned to receive the bolt when the flattened sides of the latter are aligned with the walls of the slot. At the lower end the bolt is 100

threaded and receives a nut 24, which bears against the portion 18 and which, together with the head 23, maintains the arms 10 and 11 in assembled relation. Of course, 5 when the bolt is located in one of the circular openings 20 the arms 10 and 11 may be swung together or apart in much the same manner as a pair of pliers.

When the wrench is to be used, the bolt 21 10 is first positioned in the proper opening 20 to adjust it to the size of the nut which is to be turned. The arms 10 and 11 are then swung together to bring the jaws 13 and 17 into engagement with the work. A force is 15 then applied in a clock-wise direction, speaking with reference to Figure 1. The initial effect of this force is to tighten the engagement of the jaws 13 and 17 about the nut. This is because the nut itself, and the arm 20 11, constitute in effect the operating arms of a toggle. Continued application of the force will cause the work to be turned as desired. When the work is to be released, a mere withdrawal of the turning force or slight rotation 25 in the reverse direction will effect the release.

It is important that the slot 19 be inclined to the lengths of the jaw carrying arms, as with this arrangement various advantages are obtained. In the first place, it is to be observed 30 that a good bearing surface is obtained between the forward edge 20' of each opening 20 in the slot and the curved forward face 21' of the bolt 21 in all operating positions of the jaws. When in operation, the tendency is for the force applied to cause the shorter arm to move longitudinally away from the jaw 13, and the pressure is taken between the relatively large curved contacting surfaces 20' and 21'. Also, with this arrangement, the opposed contacting surfaces between the flattened portions 15 and 18 are relatively large so that the jaw elements are held 40 against cocking or tilting laterally when they are swung relative to one another. Also, by providing an inclined slot as described, better operating effects are obtained in that the jaw 17 has a larger range of effective movement when the device is adjusted for the positions shown in Figures 1 and 3. When the 45 parts are adjusted as shown in Fig. 6, the effective range of movement of the jaw 17 is such that it will overlap the effective range of movement of the jaw 17 when the parts are adjusted as shown in Figure 1. The 50 effective range of movement of the jaw when adjusted as shown in Figure 1 is such that it will overlap the range of movement of the jaw when the parts are adjusted with the bolt 21 engaging in the outermost opening, that is, the right-hand opening, referring to 55 Figure 1.

As many changes could be made in the above construction and many apparently widely different embodiments of this invention 60 could be made without departing from

the scope thereof, it is intended that all matter contained in the above description or shown in the accompanying drawing shall be interpreted as illustrative and not in a limiting sense.

It is also to be understood that the language used in the following claim is intended to cover all of the generic and specific features of the invention herein described and all statements of the scope of the invention which, as a matter of language, might be said to fall therebetween.

What is claimed as the invention is:

In a nut wrench, in combination, an arm having a jaw substantially perpendicular to the arm, a bolt non-rotatably mounted in the arm at the end remote from said jaw face, said bolt having flattened sides which are inclined to the length of said arm and a curved bearing face facing forwardly and outwardly of said arm, a second arm having a curved jaw face on its free end and having at its other end an enlarged flattened portion with a slot inclined to the length of the arm, said slot having a plurality of openings, said bolt extending into said slot and being movable therein, and means on the bolt for maintaining the arms in assembled relation.
